[57] **CLAIM**

The ornamental design for a panel for a jewelry accessory cabinet, as shown.

DESCRIPTION

FIG. 1 is a front elevational view of a panel for a jewelry cabinet, showing my new design;

FIG. 2 is a bottom plan view thereof;

FIG. 3 is a left side elevational view thereof;

FIG. 4 is a top plan view thereof;

FIG. 5 is a right side elevational view thereof;

FIG. 6 is a front elevational view of a modified embodiment thereof;

FIG. 7 is a bottom plan view of FIG. 6;

FIG. 8 is a left side elevational view of FIG. 6;

FIG. 9 is a top plan view of FIG. 6;

FIG. 10 is a right side elevational view of FIG. 6;

FIG. 11 is a front elevational view of a second modified embodiment thereof;

FIG. 12 is a bottom plan view of FIG. 11;

FIG. 13 is a left side elevational view of FIG. 11;

FIG. 14 is a top plan view of FIG. 11;

FIG. 15 is a right side elevational view of FIG. 11;

FIG. 16 is a front elevational view of a third modified embodiment thereof;

FIG. 17 is a bottom plan view of FIG. 16;

FIG. 18 is a left side elevational view of FIG. 16;

FIG. 19 is a top plan view of FIG. 16; and,

FIG. 20 is a right side elevational view of FIG. 16.
